G. C. NELSON

VACUUM FEED SYSTEM

Filed May 13, 1921

Inventor:
Gustav C. Nelson
By: M. J. F. G.
Atty.

UNITED STATES PATENT OFFICE.

GUSTAVE C. NELSON, OF MOLINE, ILLINOIS, ASSIGNOR TO THE BORG & BECK COMPANY, OF MOLINE, ILLINOIS, A CORPORATION OF ILLINOIS.

VACUUM FEED SYSTEM.

Application filed May 13, 1921. Serial No. 469,359.

This invention relates to liquid fuel systems for explosive engines and it is particularly useful as an accessory to an automobile or truck engine.

5 The primary object of the invention is to provide means of simple and substantial construction, and comprising comparatively few and easily made parts, for connection with the fuel supply tank and the intake manifold of the engine whereby a constant and regular fuel feed to the engine will always be maintained.

Another important object of the invention is to provide for a quick "kick-over", which 15 is a term employed in the trade to indicate the change between the vacuum producing position and the atmospheric pressure position, to prevent the cut-off from fluttering or floating between positions.

20 Another important object is to provide a much larger feed chamber than has been customary heretofore, and to maintain therein a predetermined reserve supply of fuel gas by means of a small, compact 25 vacuum feed apparatus which operates sensitively and efficiently.

Another object of the invention is to provide the receiving chamber and feed chamber in separate tanks so that they can be 30 located in any convenient position and also so that the feed tank can be made in any desired size, shape or form.

Further objects of the invention are to locate the vacuum connection and air vent 35 on opposite sides of a rotary cut-off disk; to connect the receiving chamber with the feed chamber by any suitable pipe connections depending upon the relative location and arrangement of these chambers and to 40 provide a gravity or other suitable valve therein for controlling the flow of fuel gas; and to provide for straining the fuel gas as it passes from the receiving chamber to the feed chamber.

45 In the accompanying drawings illustrating a selected embodiment of the invention.

Fig. 1 is a vertical sectional view embodying the invention and

50 Fig. 2 is a detail sectional view showing another construction of the connection between the two chambers and the valve therein.

55 Referring to the drawings the feed chamber 3 is provided in a comparatively small tank 4 which has a removable head 5 secured

in place on the tank by a rod 6 which passes through the head and the bottom of the tank and is threaded to receive a nut 7. A float 8 is carried by a sleeve 9 which has a free working fit upon the rod 6 and is provided 60 at its upper end with a cut-off disk 10. This float may be provided with a conical top 8' and a conical bottom 8" as shown, but I have found that other forms may be satisfactorily used although I prefer that the 65 bottom of the float should be shaped differently from the bottom of the tank. The sleeve 9 is preferably continued down below the float, as shown at 9'.

A nozzle 11 in the head is connected by a 70 pipe 12 to the intake manifold of the engine and a nozzle 13 supported in an arm extension 14 on the head is connected to an air vent 15. These nozzles are located one above the other on opposite sides of the disk 75 10 so that the disk may have a play of $\frac{1}{64}$ to $\frac{1}{32}$ of an inch, or thereabouts, as different conditions may make desirable. The float and the disk will revolve on the rod and this keeps the disk clean and in perfect seating condition. By locating the nozzles in opposition to each other on opposite sides of the disk I overcome any tendency to a leaky seat by the disk tilting due to the loose fit on the rod or to other causes and provide for perfect seating condition at all 80 times. The supply inlet 16 preferably ends in a short pipe section 17 which discharges the fuel gas onto the top of the float. This discharge of the fuel gas against the float 90 tends to revolve the float and also tends to hold the float down until the gas level rises so high in the receiving chamber that the float is finally caused to rise quickly and make a quick "kick-over".

95 A comparatively large feed chamber 18 is provided in a tank 19 of any size, shape, or form, and this tank has an outlet 20 which is connected by a pipe (not shown) to the carburetor in the manner familiar in the art. A drain plug 21 is also located in the bottom of the feed tank. An air vent 22 is provided in the top of the feed tank. It will be noted that the receiving tank and its various parts are comparatively small 100 in size and this is possible because of the sensitive operation of the float and cut-off disk which provides an efficient means for controlling the flow of fuel gas from the supply to the receiving chamber. The feed 110

chamber may be of any desired size, shape and form and this is a desirable feature of the invention because it not only provides for the maintenance of a large reserve supply of gas in the system but it also enables the feed tank to be made in any desirable size and in a shape to fit in any part of the vehicle.

A connection 23 which may vary according to the different conditions of installations, connects the bottom of the receiving tank 4 with the side of the feed tank 19 and in this connection there is a chamber 24 and a gravity valve 25 operating therein. Beneath the chamber there is a screen 26 which is held in place by a screw cap 27 and through which the fuel gas must flow from the chamber to the feed tank.

In Fig. 2 I have shown another form of valve 28 in the connection 29 between the receiving tank and the feed tank, this valve being pivotally mounted at 30 in the connection and a cap 31 being provided to enable access to the valve and for cleaning the chamber 32.

My invention provides an apparatus of very simple construction, entirely free from delicate and complicated parts which may be made in any size, shape and form for maintaining a steady, constant, gravity fuel feed to the carburetor and a reserve fuel supply sufficient for all necessary purposes. If occasion requires the vent pipe 22 can be removed and the feed tank 19 filled through the opening in the top thereof. My system divides the apparatus into two parts which may be separated from each other and located in different parts of the automobile to accommodate different conditions. The operating part is contained in a receiving tank which may be even smaller than is indicated by the drawing; the delivery part is a supply tank from which the gas is fed by gravity to the carburetor and in which an ample supply of gas is maintained by the operating part, and these parts are connected by a pipe which may be shaped and arranged to suit the particular installation and which is provided with a valve easily accessible without disturbing the operating or delivery parts.

I am aware that changes in the form, construction and arrangement of parts of my invention may be made to suit different installations and to provide for different conditions, without departing from the spirit or sacrificing the advantages of the invention and I reserve the right to make all such changes as fairly fall within the scope of the following claims.

I claim:

1. In a vacuum feed system, two separate and independent tanks, one having a receiving chamber and the other a feed chamber, a vacuum producing connection to the re-

ceiving chamber and an air vent for said chamber, an air vent for the feed chamber, a slidably mounted float operating in said receiving tank, a cut-off disk vertically movable by said float and operating between the vacuum producing connection and the air vent of said receiving chamber to close the same alternately, a pipe connecting the receiving chamber with the feed chamber, a valve chamber in said pipe and intermediate said tanks, a valve in said valve chamber, and a removable screen between the valve chamber and the feed chamber.

2. In a vacuum feed system, two separate and independent tanks, one having a receiving chamber and the other a feed chamber, a vacuum producing connection to the receiving chamber and an air vent for said chamber, an air vent for the feed chamber, a slidably mounted float operating in said receiving tank, a cut-off disk vertically movable by said float and operating between the vacuum producing connection and the air vent of the receiving chamber to close the same alternately, a pipe connecting the bottom of the receiving chamber with the feed chamber, a valve chamber in said pipe and intermediate said tanks, a gravity valve in said chamber, a screen in the pipe between the valve chamber and the feed chamber, and a removable cap in the pipe to permit access to said screen.

3. In a vacuum feed system, a tank having a receiving chamber, a movable float having a convex top and a concave bottom arranged in said chamber, a cut-off disk rigid with said float, said float and disk being revoluble in the chamber, a vacuum producing nozzle, and an air vent nozzle for the receiving chamber, said nozzles being located on opposite sides of said disk and vertically and oppositely disposed with reference to each other.

4. In a vacuum feed system, a tank having a receiving chamber, a vacuum producing nozzle in said chamber, an air vent nozzle in said chamber opposite said vacuum producing nozzle, a vertically movable and revoluble float having a convex top and a concave bottom arranged in said chamber, a cut-off disk disposed between the nozzles and carried by the float and operated thereby to close the nozzles alternately, and a supply inlet discharging against the top of the float to resist the upward movement thereof whereby the float is finally caused to rise quickly due to the rise of the level of the liquid in the chamber and to produce a sudden and quick operation of the disk to close the vacuum producing nozzle.

5. In a vacuum feed system, a tank having a receiving chamber, a vacuum producing nozzle in said chamber, an air vent nozzle in said chamber opposite said vacuum producing nozzle, a vertically movable

- and revoluble float having a convex top and a concave bottom arranged in said chamber, a cut-off disk disposed between the nozzles and carried by the float and operated there-
5 by to close the nozzles alternately, said float having a conical top, and a supply inlet to the receiving chamber arranged to discharge against the conical top of the float.
10 6. In a vacuum feed system, a tank having a receiving chamber, a vacuum producing nozzle in said chamber, an air vent nozzle in said chamber opposite said vacuum producing nozzle, means arranged between said nozzles for alternately closing said nozzles, a float having a convex top and a concave bottom for controlling said means, and a supply inlet discharging against the top of said float to resist the upward move-
15 ment thereof, whereby said upward move-
20 ment will take place suddenly causing a quick operation of said nozzle closing means.

GUSTAVE C. NELSON.
